UNITED STATES PATENT OFFICE.

JOHN J. VERHAGEN, OF COBLESKILL, NEW YORK.

SILO-HOOP.

1,351,310.

Specification of Letters Patent. Patented Aug. 31, 1920.

Application filed June 5, 1919. Serial No. 301,984.

To all whom it may concern:

Be it known that I, JOHN J. VERHAGEN, a citizen of the United States, residing at Cobleskill, in the county of Schoharie and State of New York, have invented certain new and useful Improvements in Silo-Hoops; and I do declare the following to be a full, clear, and exact description of the invention, such as will enable others skilled in the art to which it appertains to make and use the same.

My invention, although I have termed it a silo hoop, relates to hoops not only for silos, but for tanks, vats, large barrels, hogsheads and all other objects requiring such a device; and my principal object is to provide a simple, inexpensive, easily applied, and highly efficient turnbuckle for a cable hoop which will eliminate the expense and trouble of using metal rods, nuts, etc.

With the foregoing in view, the invention resides in the novel construction described and claimed herein and shown in the accompanying drawing.

Figure 1 is a horizontal section of a silo or the like showing the device applied.

Fig. 2 is a front elevation of the parts seen in Fig. 1.

Fig. 3 is a transverse section on line 3—3 of Fig. 1.

Fig. 4 is a perspective view of one of the cable anchors.

In the drawing, the numeral 1 designates a cable for passage around silos, vats, etc., the numerals 2, refer to anchors to which the ends of the cable are secured, and 3 has reference to a double acting screw for drawing said anchors together to tighten the cable.

Each anchor 2 is provided preferably with two openings 4 through which the cable ends are looped, and with a threaded opening 5 for the screw 3, and although I preferably form said anchors of rectangular form, it is only essential that they be provided with one straight edge 6 or its equivalent

for contact with the silo or the like to hold the anchors against turning when the screw 3 is either tightened or loosened.

The cable ends may be secured in any preferred manner as by clamps 7, and adequate provision, such as the hexagonal center 8 may be made for turning the screw by a wrench, and due to the edges 6, the cable ends will not be twisted when turning said screw. By means of this screw, or perhaps one swiveled in one opening 5 and threaded in the other, the loop may be tightly contacted around the object circumscribed thereby, and may of course be as easily loosened.

The device is simple, easy and inexpensive to manufacture, easy to apply and adjust, and highly efficient in every way, doing away entirely with expensive metal rods, nuts and other hardware now commonly used.

Since probably the best results may be obtained from the details disclosed, they may well be followed, but within the scope of the invention as claimed, numerous minor changes may well be made.

I claim:

A turnbuckle for cable hoops comprising two substantially flat, truly rectangular blocks of identical size and shape and unobstructed on all sides and edges, each block having one edge for contact with a cable-encircled object and having a pair of cable receiving openings adjacent said edge, each block having near its opposite edge a single central opening, all of said openings leading from one flat side of the block to the other flat side thereof, and a screw passing through said central opening of each block.

In testimony whereof I have hereunto set my hand.

JOHN J. VERHAGEN.
